UNITED STATES PATENT OFFICE

159,210

LID

Harry E. Jones, Norwood, Pa.

Application March 16, 1949, Serial No. 1,416

Term of patent 3½ years

(Cl. D58—26)

To all whom it may concern:

Be it known that I, Harry E. Jones, a citizen of the United States of America, residing at Norwood, in the county of Delaware and State of Pennsylvania, have invented a new, original, and ornamental Design for a Lid, of which the following is a specification, reference being had to the accompanying drawing, forming part thereof.

In the drawing, Fig. 1 is a view in side elevation of a lid showing my new design, and

Fig. 2 shows the top plan of the lid.

I claim:

The ornamental design for a lid, as shown.

HARRY E. JONES.
